UNITED STATES PATENT OFFICE.

WILLIAM P. LEVY, OF SALINAS, CALIFORNIA.

TENSIONING DEVICE FOR CLOTH-FOLDING MACHINES.

Application filed September 1, 1922. Serial No. 585,812.

To all whom it may concern:

Be it known that I, WILLIAM P. LEVY, a citizen of the United States, and a resident of Salinas, in the county of Monterey and State of California, have invented a new and Improved Tensioning Device for Cloth-Folding Machines, of which the following is a full, clear, and exact description.

This invention relates to improvements in cloth folding machines, and has particular reference to a cloth tensioning device therefor.

An object of the invention is to facilitate the folding of cloth upon a cutting table by applying a tension to the cloth as the same is fed to the operator, thus permitting the cloth to be uniformly laid upon said table.

Another object is to permit of the tension on the cloth being regulated so as to compensate for various thicknesses and textures thereof.

The above and other objects will appear more clearly from the following detail description when taken in connection with the accompanying drawing, which illustrates a preferred embodiment of the inventive idea.

In the drawing—

Figure 1 is a conventional illustration of a cloth folding machine showing the invention applied thereto;

Figure 2 is an enlarged detail end elevation of the tensioning device; and

Figure 3 is a top plan view thereof.

Referring more particularly to the drawing, the numeral 4 indicates generally a cloth folding machine which includes a supporting member 5 arranged in an inclined position and supporting adjacent one end a cloth feeding mechanism 6 of any construction well known in the art. The tensioning device, generally indicated at 7, which comprises the essential features of the present invention, is secured to the supporting member 5 at the opposite end from the feeding mechanism and is designed to apply tension to the cloth 8 as it is fed from the bolt or bail 9 by the feeding mechanism 6 to the operator who is positioned before the cutting table 10. By applying a tension to the cloth at the point of delivery from the machine to the cutting table, it will be apparent that the operator may withdraw the necessary quantity of cloth from beneath the tension-

ing device 7 and fold the same upon the cutting table 10 in uniform layers preparatory to making the cutting operation.

Specifically the tensioning device comprises a base 11 mounted upon the supporting member 5 and provided along its forward longitudinal edge with a plate 12 over which the cloth to be folded upon the table 10 is passed. Rearwardly of the plate 12 the base 11 has secured thereto bearings 13, in which is mounted an oscillatory shaft 14, to which are secured a plurality of forwardly extending tensioning elements 15, preferably in the form of flat springs having their forward free edges disposed above the plate 12 so as to exert a pressure upon the cloth 8 which passes beneath said springs.

Secured to one end of the shaft 14 is a lever 16 to which movement is imparted by an operating member 17 to oscillate the shaft 14 in its bearings 13, whereby the tensioning elements 15 may be adjusted back and forth with respect to the plate 12 in order that the tension upon the cloth passing over the plate 12 and beneath said tensioning elements may be regulated. The end of the lever 16 opposite to that end which is secured to the shaft 14 has mounted thereon in a stub shaft 18 provided with a bearing 19 through which the operating member 17 extends. A set screw or other suitable locking device 20 is carried by the bearing 19 and when the tensioning elements 15 have been adjusted to exert the desired pressure upon the cloth, the locking device 20 is rotated until the same engages the operating member 17 and thus prevents relative movement between said member and the lever 16. The lower end of the operating member 17 is pivotally mounted in a bearing 21 carried by the base 11 of the device, so that as said operating member is moved forwardly and rearwardly about its pivot a relative sliding movement is produced between the operating member 17 and the lever 16, whereby the shaft 14 is rotated in its bearings to produce the result previously referred to.

After making the proper adjustment of the tensioning elements 15, the operator may slide a stop or abutment 22 mounted upon the operating member 17 longitudinally of said member until said stop engages the bearing 19, whereupon the set screw or other locking device 23 carried by the stop 22 is

engaged with the member 17. Should the operator then desire to relieve the tension upon the cloth for any reason and afterward would wish to secure the same tension, 5 he may do so by disengaging the locking device 20 from the member 17, whereupon the lever 16 and bearing 19 will move longitudinally with respect to the operating member 17 under the influence of the tensioning 10 elements when the same are restored to their normal condition. Now when the operator again desires to apply tension to the cloth the free end of the operating member 17 is pulled forwardly causing a downward 15 movement of the adjacent end of the lever 16 until the bearing 19 contacts with the stop 22, at which time the former tension which has been applied to the elements 15 is again obtained, whereupon the operator may 20 again engage the locking device 20 with the member 17 and thus maintain the desired adjustment of the tensioning elements.

What is claimed is:

1. In a tensioning device, an oscillatory shaft, tensioning elements carried thereby, and relatively movable members having a sliding engagement with each other for oscillating said shaft to control the tension of said tensioning elements.
2. In a tensioning device, an oscillatory shaft, tensioning elements carried thereby, relatively movable members having a sliding engagement with each other for oscillating said shaft to control the tension of said tensioning elements, and means for locking said members in an adjusted position to maintain constant the tension of said tensioning elements.
3. In a tensioning device, an oscillatory shaft, tensioning elements carried thereby, relatively movable members having a sliding engagement with each other for oscillating said shaft to control the tension of

said tensioning elements, and means for limiting the relative movement of said members. 45

4. In a tensioning device, an oscillatory shaft, tensioning elements carried thereby, relatively movable members having a sliding engagement with each other for oscillating said shaft to control the tension of said tensioning elements, means for locking said members in an adjusted position to maintain constant the tension of said tensioning elements, and means for limiting the relative movement of said members in one direction. 50 55

5. In a tensioning device, an oscillatory shaft, tensioning elements carried thereby, relatively movable members having a sliding engagement with each other for oscillating said shaft to control the tension of said tensioning elements, and means carried by one of said members for limiting the relative movement of the other member with respect thereto. 60 65

6. In a tensioning device, an oscillatory shaft, tensioning elements carried thereby, relatively movable members having a sliding engagement with each other for oscillating said shaft to control the tension of said tensioning elements, and means adjustable longitudinally of one of said members to limit the movement of the other member in one direction. 70 75

7. In a tensioning device, an oscillatory shaft, tensioning elements carried thereby, a lever secured at one end of said shaft, an operating member having a sliding connection with said lever and a relative movement with respect thereto for adjusting said lever whereby said shaft and tensioning elements are oscillated, and means engageable with said operating member for maintaining said lever in an adjusted position. 80

WILLIAM P. LEVY.
